UNITED STATES PATENT OFFICE.

WILLARD C. BRINTON, OF NEW YORK, N. Y.

JACK.

1,267,051.

Specification of Letters Patent. Patented May 21, 1918.

Application filed August 26, 1916. Serial No. 117,031.

To all whom it may concern:

Be it known that I, WILLARD C. BRINTON, a citizen of the United States of America, and a resident of New York, county and 5 State of New York, have invented certain new and useful Improvements in Jacks, of which the following is a specification, reference being had to the accompanying drawings, forming a part thereof.

10 My invention relates to elevating or lifting jacks and has special reference to jacks of the screw type.

In my copending application Serial No. 802,192, filed November 21, 1913, of which 15 this application is a continuation in part, I have shown and described a motor truck which is particularly adapted for handling freight on platforms and is equipped with elevating jacks at its corners.

20 My present invention pertains to jacks which are specially adapted for this purpose, although it will of course be understood that my jack may be used in various ways and I only intend that such limitations 25 be imposed as are indicated in the appended claims.

One object of my invention is to provide a jack that shall be relatively simple and particularly durable and compact in construction and that shall be fully protected 30 from dirt and from injury, and particularly adapted for its intended purpose.

In order that my invention may be thoroughly understood I will now proceed to describe the same in the following specification, and then point out the novel features thereof in appended claims.

Referring to the drawings:

Figure 1 is a sectional elevation of a jack 40 arranged and constructed in accordance with, and constituting an embodiment of, my invention.

Figs. 2 to 5 inclusive are sectional plan views taken respectively on the lines 2—2, 45 3—3, 4—4 and 5—5 of Fig. 1.

Fig. 6 is a view corresponding to Fig. 1, of a slightly different structure which embodies my invention.

Special reference may first be had to Figs. 50 1 to 5 inclusive in which 10 designates the platform frame of a truck or vehicle and 11 the housing which is secured to the frame by any suitable means such as bolts 12, and forms a part of the jack. The housing 55 has the form of a sleeve with a constricted lower end to provide a guide bearing 13 and

an enlargement near its upper end to provide a guide bearing 14. It has a yoke formation at the top to support a guide bushing 15. 60

In addition to the housing the jack comprises a spindle or jack screw 16, an actuating thimble 17, and a lifting or elevating quill 18 which is arranged to slide up and down within the thimble 17, but is prevented 65 from turning by keys 19.

Adjacent to the guide bearing 13 is a frictionless thrust bearing 20, and I prefer to utilize bearing rollers 21 for the guide bearing 14. 70

The spindle 16 has a screw-threaded upper section 22, a recess 23 at the top, a square or polygonal enlargement 24 below the threaded section, and a cylindrical section 25 at the bottom which extends through the 75 thrust bearing 20 and the guide bearing 13. The extreme lower end is screw-threaded as indicated at 26, to receive a nut 27 which holds a flange or collar 28 in place.

One of the thrust collars 29 of the frictionless bearing 20 is in engagement with the square enlargement 24 to support the downward thrust upon the spindle and the collar 28 overhangs the lower end of the housing 11 and prevents the spindle from 85 being displaced upwardly.

The housing is closed by a cap 30 which is screwed onto its lower end.

The thimble 17 is rotatably mounted in the roller guide bearing 14 and has a square 90 opening 31 which fits the square enlarged section 24 of the spindle. At the top of the thimble are a plurality of outwardly extending lugs 32 to which a sprocket wheel 33 is secured by bolts 34 or other suitable 95 means.

The sprocket wheel has an annular projection 35 which overhangs the upper end of the body of the housing to prevent extraneous matter from getting into the guide 100 bearing 14 and into the thimble (see Fig. 1).

The arrangement of parts is such that when the sprocket wheel 33 is driven the motion is transmitted through the thimble to actuate the spindle. The spindle itself, 105 when actuated, does not advance, being held in fixed vertical position by the thrust bearings as already explained, but the turning of the screw-threaded section of the spindle 22 causes the quill 18 to be elevated as I will 110 now explain.

The quill has a flange 36 at its lower end

which fits freely into the body of the thimble 17 and extends almost to the square enlargement 24 of the spindle in its bottom position. It has an internally threaded constricted 5 section 37 which co-operates with the screw-threaded section 22 of the spindle, and it is preferably formed of Babbitt or some suitable bearing metal which is cast into the lower end of the quill 18.

10 The quill has longitudinal slots or keyways 38 to co-operate with the keys 19 so that it is prevented from rotating with the spindle. A plug 39 is screwed into the mouth of the quill as shown in Fig. 1.

15 A plug 40 is set into the recess 23 and in the ends of the spindle and forms a raceway for a plurality of bearing balls 41 upon which a rotatable stop lug 42 is mounted. The upper end of this stop engages the plug 20 39 of the quill 18 when the quill is at the bottom of its movement.

As already explained, the housing has the form of a yoke at the top and the upper extension of this yoke provides a ring 43 from 25 which a plurality of spaced lugs 44 extend inwardly as shown in Fig. 2.

The bushing 15 has a top flange 45 which is perforated to receive bolts 46 and overhangs the lugs 44 of the housing to which 30 it is secured by the bolts.

The bushing has an overhanging flange 47 which interlocks with an upwardly extending annular projection 48 of the sprocket wheel 33, the outer surface of the bushing 35 being formed to fit freely into the sprocket wheel and into the upper end of the thimble 17.

The bushing has a cylindrical bore of suitable size to receive, and constitute a guide 40 bearing for, the quill 18.

The bushing is provided with key slots 49 which extend downwardly to an intermediate point in the length of the bushing where they terminate in through-holes 50.

45 These holes facilitate the cutting of the keyway by providing an outlet for the tool in a well known manner and also constitute sockets which receive laterally extending lugs 51 which are riveted or otherwise secured to the keys 19 at their lower ends. The bushing 15 is provided near the top with an annular groove 76 with which one or more slots or discharge openings 77 communicate. Oil and dirt are collected in the 55 groove and are discharged through the slots 77 into the drip pan or receptacle formed by a flange 52 in the housing.

The aforesaid co-operating parts facilitate the assembling of the device which will now 6 be explained. The spindle and thimble are first secured together and are then mounted in the housing. The sprocket wheel 33 is not attached to the thimble and the thimble lugs 32 are turned so as to avoid interfering 65 with the housing lugs 44 until the thimble is

in its proper longitudinal position relative to the housing. It is then turned to a slight angle to bring the bolt holes in the lugs 32 into register with the bolt holes in the lugs 44. The sprocket wheel 33 is next introduced laterally between the yoke connected sections of the housing and is fitted onto the thimble. The bolts 34 have slotted heads and are driven into place by a screw driver which extends through the bolt hole in the 75 housing lugs 44. The quill 18 is next screwed onto the spindle, then the plugs 40 and 42, together with the bearing balls 41, are set into the recess 23 of the spindle.

The keys 19 are next set into the keyways 80 49 of the bushing 15 with the lugs 51 extending into the sockets 50; then the bushing is mounted in position, the keys 19 engaging the keyways 38 of the quill. The bushing is held in place by the bolts 46 85 which engage the housing lugs 44 as already explained. Finally, the plug 39 is screwed into the top of the quill 18.

Before describing the structure shown in Fig. 6, I will discuss the operation of that 90 already described. Assuming that the parts occupy the positions as shown in the drawings, if the sprocket wheel 33 is driven in one direction by a sprocket chain or other suitable actuating means, the thimble 17 to 95 which it is attached, is correspondingly rotated in the roller bearings 14. The spindle 16, which, as already explained, bears a fixed relation to the thimble, is also rotated with the result that the quill together with 100 the plug 39, is elevated. The spindle itself is held in a fixed longitudinal position by the thrust collars 20 and 29 and the quill is prevented from turning by the keys 19 as already explained, so that the longitudinal 105 movement of the quill results.

If the actuation of the sprocket wheel 33 continues, the quill 18 is elevated until the flange or enlargement 36 of the quill comes into engagement with the lower end of the 110 bushing 15.

If the direction of rotation for the sprocket wheel is now reversed the spindle turns in the opposite direction and the quill 18 is lowered. The downward movement of 115 the quill is limited by the engagement of the top of the plug 42 with the inner surface of the plug 39.

The frictionless bearings 41 prevent the locking of the quill in its bottom position, 120 due to the setting of the quill plug against the end of the spindle. This is evidently accomplished by the arrangement shown since the spindle plug may remain stationary when the spindle is first turned.

Attention is particularly directed to the fact that the overhanging projections 47 and 35 completely close the housing and prevent dirt from getting into the bearings. Any oil or grease which may work out of 130

the bearings and housing will be collected in the drip pan or receptacle formed by the flange 52. The cap 30 seals the housing at the bottom and hence the structure is particularly well adapted to extend downwardly from the frame of a motor vehicle.

It will also be observed that when the quill is lowered its top surface is flush with the floor of the vehicle body. The structure 10 shown in Fig. 6 is similar in general to that of the previous figures and comprises a flanged ring 57 which reinforces the opening in the floor plate and is slotted to receive the keys 55. It constitutes a bearing 15 for the upper end of a quill 54, the lower end of which is enlarged to fit the hollow cylindrical opening in the thimble 53. The arrangement is such that an annular shoulder 58 is provided to limit the outward 20 movement of the quill 54 by engaging the flanged reinforcing ring 57. The quill 54 is provided with a central opening which is constricted near its lower end and is tapped to engage the threaded portion of the spindle 62. The upper part of the hoisting 25 member is hollow to form a grease-cup 59 and is closed by a plug 60.

The spindle 62 has a collar 63 which rests on a shoulder 64 of the thimble 53. The 30 lower part of the spindle which is below the collar, is preferably pressed into a suitable hole in the bottom of the thimble and is firmly secured to the thimble by a key 65 or other suitable means. An annular thrust 35 bearing 66 is mounted within the cup-shaped bracket 67 at the bottom, and supports the thimble 53 and the spindle which is secured to it.

The thimble at its upper end, is fitted onto 40 the lower part of the flanged ring 57 which constitutes a guide bearing. Opposite this bearing, near the upper end of the thimble, is a sprocket wheel 68 which is engaged by a hoisting chain 69.

45 Rotatably mounted on the thimble adjacent to the sprocket wheel is a sheave 70 which constitutes a guide for the steering cable 71.

The lower end of the spindle is guided 50 by a bearing 72 in the bracket 67, the bearings 66 and 72 being supplied with lubrication through grease passages 73 which communicate at the lower end of the spindle with a compression grease cup 74.

55 Other modifications may be effected within the spirit and scope of my invention, and I intend that only such limitations be imposed as are indicated in appended claims.

What I claim is:

60 1. A hoisting jack adapted to be mounted flush with a floor or deck, comprising a stationary housing affixed at the floor or deck, a thimble rotatably mounted therein with a bearing near the top, a spindle extending through said housing and said

thimble and secured to said thimble near the bottom, and a hoisting quill mounted to slide within said thimble and adapted to be raised and lowered by the rotation of said spindle.

70 2. A hoisting jack adapted to be mounted flush with a floor or deck, comprising a stationary housing affixed at the floor or deck, a thimble rotatably mounted therein with a bearing near the top, a spindle extending through said housing and said thimble and secured to said thimble near the bottom, a hoisting quill mounted to slide within said thimble and adapted to be raised and lowered by the rotation of said spindle, 75 and rotatable means for stopping the descent of hoisting quill when its top is flush with the floor or deck.

80 3. A hoisting jack adapted to be mounted flush with a floor or deck, comprising a relatively stationary cup-shaped supporting housing affixed at the floor, a thrust bearing near the bottom of the housing, a thimble rotatably mounted on said thrust bearing within said cup-shaped housing and adapted to 85 have power applied to it at the top, a screw-threaded spindle extending through said housing and said thimble and secured to said thimble, a hollow cylindrical hoisting quill flush with the floor when retracted and 90 mounted to slide within said thimble and screwed onto said spindle, and means for preventing the rotation of the hoisting quill whereby the said quill is elevated by the rotation of the thimble and the spindle. 95

100 4. A hoisting jack adapted to be mounted flush with a floor or deck, comprising a relatively stationary cup-shaped supporting housing affixed at the floor and having a vertical guide bearing at its lower end and an annular frictionless thrust bearing near its lower end above the guide bearing, a thimble rotatably mounted on said thrust bearing within said housing, a screw-threaded spindle extending vertically through said 105 thimble and secured thereto and supported at its lower end in said guide bearing, a hoisting member mounted to slide vertically within said thimble and screwed onto said spindle above the point of connection thereof with the thimble, a relatively stationary guide bushing at the top of the thimble, keys set in said bushing for preventing the rotation of the hoisting member, and a sprocket wheel secured near the upper edge 110 of the thimble whereby the rotation of the sprocket wheel and the consequent turning of the thimble and a spindle serves to elevate the hoisting member, the top of said member being flush with the floor in its 115 retracted position.

120 5. A hoisting jack for a truck platform comprising a supporting housing depending from the platform frame, a screw-threaded spindle rotatably mounted therein and held 125

- against longitudinal movement thereby, a screw-threaded hoisting member coöperating with the spindle and flush with the platform at the top when retracted, a thimble affixed to the spindle and extending around the hoisting member, and means for driving the thimble to actuate the hoisting member.
6. A hoisting jack adapted to be mounted flush with a floor or deck, comprising a relatively stationary housing affixed at the floor or deck and extending downwardly therefrom, a bushing secured to the housing near the top with its upper end flush with the floor or deck, a spindle extending into the housing and arranged to be rotated therein, a hoisting member mounted to slide vertically in the bushing and adapted to extend downwardly into the housing with its top flush with the floor or deck in its retracted position, and means adapted to have power applied to it at a point near the floor for turning the spindle.
7. A hoisting jack adapted to be mounted flush with a floor or deck, comprising a relatively stationary cup-shaped housing secured to the floor or deck near its upper end and extending downwardly therefrom, a screw-threaded spindle rotatively mounted within the housing and supported near the lower end thereof and a hoisting member threaded near its lower end to coöperate with the spindle and extending into the

housing with its upper end flush with the floor in its retracted position, means for preventing the rotation of the hoisting member, and means for turning the spindle.

8. A jack for a truck platform comprising a housing having a cup-shaped body and a spaced integral ring at the top, a screw-threaded spindle rotatively mounted within the housing, a thrust bearing for preventing longitudinal movement of the spindle relative to the housing, a thimble affixed to the spindle near its lower end and extending slightly above the cup-shaped body of the thimble, a sprocket wheel secured to the thimble at the top, a hollow cylindrical quill surrounding the spindle and having an internally threaded portion coöperating with the spindle, a stationary threaded portion coöperating with the spindle, a stationary bushing secured to the ring member of the housing and extending between the thimble and the quill, keys mounted in the bushing for holding the quill against rotation and a cap for closing the upper end of the quill over the top of the spindle, whereby the quill may be raised and lowered by actuating the sprocket wheel.

In witness whereof, I have hereunto set my hand this 24th day of August, 1916.

WILLARD C. BRINTON.
